WILLIAM MANNHEIM, OF NEW YORK, N. Y.

Letters Patent No. 69,229, dated September 24, 1867.

IMPROVED MACHINE FOR TAPERING LEATHER.

The Schedule referred to in these Letters Patent and making part of the same.

TO ALL WHOM IT MAY CONCERN:

Be it known that I, WILLIAM MANNHEIM, of the city, county, and State of New York, have invented a new and improved Machine for Tapering Leather; and I do hereby declare that the following is a full, clear, and exact description thereof, which will enable those skilled in the art to make and use the same, reference being had to the accompanying drawings, forming part of this specification, in which—

Figure 1 represents a vertical longitudinal sectional view of my improved leather-tapering machine, the plane of section being indicated by the line $x x$, fig. 2.

Figure 2 is a plan or top view of the same.

Figure 3 is a front elevation partly in section of the same.

Similar letters of reference indicate corresponding parts.

This invention relates to a machine in which the edges of leather straps can be bevelled or tapered, and also the ends of the same, but in which, when desired, the leather can also be scraped or shaved so as to be reduced in thickness to an equal degree throughout.

The invention consists in the arrangement of a knife or cutter, which is hinged at one end to a stationary frame, while its other end is adjustable up and down, and in the use, in combination with the above, of an up and down adjustable frame, on which a friction-roller is held, the axis of which is directly under the cutting edge of the knife; said roller being the bearing for the leather, its greater or less distance from any part of the cutting edge of the knife indicating the thickness of leather, as the same will be cut.

For tapering the ends of leather belts a sliding frame is arranged by which the roller is gradually raised toward the knife, thereby gradually decreasing the distance between the said roller and the cutting edge of the knife, and consequently also the thickness of leather toward the end of the belt. By means of set-screws the degree of inclination can be varied and regulated at pleasure.

A represents a level cast-iron or other bed-plate, which is provided with downward flanges, or with countersunk holes, or which is otherwise so arranged that it can easily be screwed or secured to the edge of a stationary table, B, which is shown by red lines in fig. 1. From the ends of the bed-plate A project upward the vertical arms b and c, which are clearly shown in figs. 2 and 3. From the upper end of the arm b project two lugs or ears d d, which are the bearings for a pin, e, around which one end of a cutter, C, is hinged. The other end of the latter is hinged by a pin, f, to a horse-shoe-shaped bar, g, through the slot of which a set-screw, D, passes, for which the nut is formed in the upright e, and which is provided with shoulders h h, by which it engages the bar g and moves it up or down, as it is turned in the one or other direction, (see fig. 3.) The knife C can thus be set in an inclined position, the angle being varied at pleasure by means of the said set-screw D. The bar g is necessary, as it prevents the knife from being strained, which would be the case unless the knife or the set-screw is jointed. As it is arranged the bar g will always remain level, the slot permitting an easy self-adjustment as the position of the knife C is varied. When the bar g is screwed down so as to touch the top of the arm c the cutting edge of the knife will be level. E is a frame which is pivoted by pins i i to the lower part of the uprights b c, and which extends across the whole width of the bed-plate A; the pivots being on the inner side, while its free or swinging part is on the outer side of the same, as is clearly shown in fig. 1. About midway between the free and the pivoted sides of the frame E is pivoted to the same, by means of pins j j, an upright frame, F, in which the bearings for a horizontal roller, G, which extends along the whole length of the machine, and the axis of which is directly below the cutting edge of the knife C. By a spring, H, the frame F is pressed against the uprights b c, while set-screws R R keep it off, and thus the axis of the roller can be moved toward the knife when the cutting edge is worn. A set-screw, l, arranged in the bed-plate A, under the free end of the frame E, serves to raise the frames E and F, and consequently also the roller G, more or less toward the knife, as is indicated by red lines in fig. 1. I is a bar, having its bearings in the frame, and being parallel with the roller G, but somewhat elevated above the same. It is arranged so as to slide in its bearings, and so that it can be easily drawn out of the same, but can be fastened by a set-screw, m. A sliding block, J, is fitted upon the bar I, and reaches to the roller G, as is clearly shown in the drawing. It slides loose on the bar I, and can be fastened in any position by a set-screw, n.

The operation is simple and as follows: The knife is set by the screw D to the desired angle. By the set

screw *l* the distance between the lower end of the cutter and the roller *G* is adjusted. Then the block *J* is moved on the bar *I* so that the distance between it and the upright *b* will be equal to the width of the leather strap to be cut. The end of the leather is then inserted under the cutter by swinging the frame *F* back against the spring *H*, for which purpose a handle, *o*, is provided on the frame *F*. Then the latter is, by the spring *H*, again forced against the uprights *b* *c*. Then the leather is drawn through in the direction of the arrow in fig. 1, and will then be cut or tapered in the manner indicated by red lines in fig. 3. If both edges are to be tapered, the strap, after having once passed through the machine, is once more drawn through the same, but with the opposite end. The block *J* serves to keep the strap in position and prevent it from being cut unevenly or irregular. When the strap is only to be shaved, so that both sides are parallel, the free end of the cutter is lowered as far as possible, and the roller *G* is adjusted by the screw *l* in accordance with the desired thickness of material. When the device is to be used for tapering the ends of straps for belting and other purposes the knife is arranged level, but the set-screw *l* is removed, and in its place a frame, *L*, is arranged between the frame *E* and the plate *A*, as is clearly shown in fig. 1. This frame *L* has an upward extension at the outer side, on which an elevated platform, *p*, is formed, as shown. Upon the lower horizontal or level platform *q* of the frame *L* is hinged to the outer side a frame, *r*, the inner side of which is held up by a set-screw, *s*, by which its angle of inclination is adjusted. When to be used this frame *r* is so adjusted in accordance with the required slope, the whole frame *L* is moved in as far as necessary. The free end of the frame *E* rests on the frame *r*, as shown. The latter is then inserted in the manner hereinbefore described, but so that only that portion of it which is to be tapered projects beyond the cutting edge of the knife. Then the block *J* is adjusted on the bar *I*. As the strap hangs over the platform *p* of the frame *L*, the strap and platform are jointly taken hold of and are then pulled in the direction of the arrow, fig. 1. The frames *E* and *F* will then be gradually elevated as the frame *L* is being pulled out, and thereby the roller *G* is gradually raised toward the edge of the knife, thereby diminishing the space for the leather to pass through, and tapering it in the required degree. By the springs *t* the frame *E* is forced down, so that it will be easily lowered as well as raised.

Claim.

1. A machine in which leather straps can be shaved or bevelled, or their ends tapered, which is arranged so as to be adapted to every width and thickness of leather, and which will operate substantially in the manner herein shown and described.
2. The jointed and hinged knife or cutter *C*, when arranged on the stationary frame so as to be adjusted in position by the screw *D*, substantially as and for the purpose herein shown and described.
3. The removable rod *I*, when provided with the adjustable sliding block *J*, in combination with the roller *G* and cutter *C*, all made and operating substantially as herein shown and described.
4. The sliding frame *L*, when provided with a handle *p*, in combination with the frame *r*, set-screws *s*, frames *E* and *F*, roller *G*, and cutter *S*, all made and operating substantially as herein shown and described.
5. The hinged jointed cutter *C*, in combination with the roller *G*, all made and operating substantially as set forth.
